UNITED STATES PATENT OFFICE.

FRANK R. STAFFORD, OF NEWARK, NEW JERSEY.

BRACELET COUPLING.

Application filed August 9, 1920. Serial No. 402,194.

To all whom it may concern:

Be it known that I, FRANK R. STAFFORD, a citizen of the United States, and a resident of Newark, in the county of Essex and State 5 of New Jersey, have invented a new and Improved Bracelet Coupling, of which the following is a full, clear, and exact description.

This invention relates to jewelry and particularly to an improved coupling for flexible bracelets, which is an improvement over my co-pending application, Serial No. 370,046, and has for an object to provide a construction which is simply and easily 10 manufactured and which will properly hold together parts of the bracelet and at the same time allow the bracelet to flex in the desired manner.

Another object of the invention is to provide 20 a coupling for holding together boxes of a flexible bracelet, the arrangement being such that the boxes are not only articulated but are prevented from twisting.

A further object of the invention is to provide 25 a coupling which may be stamped or formed out partially complete and then completed after it has been placed in position so as to permanently lock the parts together co-acting therewith.

30 In the accompanying drawing—

Figure 1 is a sectional view through Figure 2 on line 1—1, the same disclosing part 35 of the flexible bracelet with coupling means embodying the invention applied thereto.

Figure 2 is a sectional view through Figure 1 on line 2—2.

Figure 3 is a plan view of a coupler ready to be applied.

Figure 4 is a view similar to Figure 3 but 40 showing a slightly modified construction.

Referring to the accompanying drawing by numerals 1 indicates boxes forming part of a bracelet, said boxes being provided with openings 2 for receiving stones to be set 45 therein and openings 3 through which the couplers 4 are passed. The boxes 1 are beveled or chamfered at 5 and 6 so that they may be formed into a circle or substantially a circle to properly fit the wrist of the person 50 without separating the outer face.

It will be noted that the openings 3 are near the face carrying the stones so that the

pivotal or hinged connection produced by the couplers 4 extending therethrough presents the hinge structure near the ornamental face of the bracelet without presenting any objectionable hinged structures on said ornamental face.

As indicated in Figure 1, the slots 3 elongate transversely so as to receive the flat 60 body 7 of the coupler 4. A pair of shoulders 8 and 9 extend from one end of body 7 and are designed to engage one of the boxes 1 while the end 10 is collapsed or pressed into the shape shown in Figure 1 in order to 65 produce projections or shoulders 11 and 12 which co-act with the shoulders or projections 8 and 9. This arrangement produces a simple coupling and one which cannot accidentally get out of order or become 70 displaced while at the same time in view of the flat nature of body 7, the respective boxes 1 cannot twist or independently rotate.

In applying the couplers 4 they are inserted as shown at the right of Figure 1 and 75 then the extreme end is pressed by a suitable tool so as to collapse said end, which end is provided with an opening 13 to permit said collapsing to the position shown at the left in Figure 1. This completed coupler therefore 80 presents a flat body with integral enlargements or heads at each end.

In Figure 4 will be seen a slightly modified form of coupler 4' in which opening 13' is elongated. This construction is designed 85 more particularly for very small boxes and the end carrying the opening 13' must be spread by the insertion of a round or other suitable shaped tool before the apertured end can be collapsed.

It will be understood of course, that the drawing shows all of the parts on a larger scale than is usually used, though for certain classes of work this size or even large couplings may be utilized.

What I claim is:

1. A coupler for flexible bracelets and the like comprising a flat body formed with shoulders extending laterally beyond the edges of the body at one end and at the opposite end with a hollow collapsible extension so positioned that when collapsed it will form shoulders also extending beyond the edges of the body.

2
2. A flexible bracelets and coupling, comprising a plurality of boxes, each box having an opening in opposite walls, and a coupling member loosely mounted so as to extend through the openings of adjacent boxes, each of said coupling members comprising a body formed with a shoulder extending laterally

beyond the edges at one end and at the opposite end with a collapsible extension so positioned that when collapsed it will form shoulders extending beyond the edge of the body at the opposite end thereof.

FRANK R. STAFFORD.
